Primary Examiner — Jennifer Rivard*Assistant Examiner* — Catherine S Posthauer(74) *Attorney, Agent, or Firm* — Adam K. Sacharoff; Much Shelist, PC(57) **CLAIM**

The ornamental design for a pan, as shown and described.

DESCRIPTION

FIG. 1 is a front side perspective view of a first embodiment of a pan, showing my new design;

FIG. 2 is a left side view thereof;

FIG. 3 is a right side view thereof;

FIG. 4 is a front view thereof;

FIG. 5 is a rear side view thereof;

FIG. 6 is a top plan view thereof;

FIG. 7 is a bottom plan view thereof;

FIG. 8 is a bottom perspective view thereof;

FIG. 9 is a front side perspective view of a second embodiment of the pan, showing my new design;

FIG. 10 is a left side view thereof;

FIG. 11 is a right side view thereof;

FIG. 12 is a front view thereof;

FIG. 13 is a rear side view thereof;

FIG. 14 is a top plan view thereof;

FIG. 15 is a bottom plan view thereof; and,

FIG. 16 is a bottom perspective view thereof.

The evenly broken lines represent parts of the article that form no part of the claim. The dot-dash lines represent the boundaries of the claim and form no part thereof.

1 Claim, 10 Drawing Sheets
